(57) **CLAIM**

The ornamental design for a case for electronic communications device, as shown and described.

DESCRIPTION

FIG. 1 is a front perspective view of a case for electronic communications device showing my new design in an environment of use;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view showing an environmental inner shell in isolation for clarity of disclosure;

FIG. 10 is a rear perspective view showing the environmental inner shell in isolation for clarity of disclosure;

FIG. 11 is a front perspective view showing the case for electronic communications device in isolation for clarity of disclosure;

FIG. 12 is a rear perspective view showing the case for electronic communications device in isolation for clarity of disclosure;

FIG. 13 is an exploded front perspective view showing the case for electronic communications device separated from the environmental inner shell for clarity of disclosure; and, FIG. 14 is an exploded rear perspective view showing the case for electronic communications device separated from the environmental inner shell for clarity of disclosure.

The dashed broken lines throughout the drawing figures depict environmental subject matter and portions of the case for electronic communications device that form no part of the claimed design.
